Fig. 2

Fig. 3

Fig. 4

Fig. 5

Fig. 6

FIG. 1 is a front perspective view of a dictating machine with extensible microphone rack or the like showing our new design;

FIG. 2 is an elevational view of the dictating machine, showing the side from which the microphone rack extends.

FIG. 3 is an elevational view showing the other side of the dictating machine.

FIG. 4 is a top plan view of the dictating machine.

FIG. 5 is a rear view of the dictating machine, the microphone rack being shown in its retracted position.

FIG. 6 is a front view of the dictating machine, the microphone rack being shown in its retracted position.

The underside of the dictating machine is conventional.

We claim:

The ornamental design for a dictating machine with extensible microphone rack or the like, as shown and described.
